UNITED STATES PATENT OFFICE.

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

MACHINE FOR MOUNTING SHOES ON LASTS.

1,318,499.

Specification of Letters Patent.

Patented Oct. 14, 1919.

Application filed December 14, 1917. Serial No. 207,101.

To all whom it may concern:

Be it known that I, NORWOOD H. KNOWLTON, a citizen of the United States, residing at Rockport, in the county of Essex, and 5 State of Massachusetts, have invented certain Improvements in Machines for Mounting Shoes on Lasts, of which the following description, in connection with the accompanying drawings, is a specification, like reference characters on the drawings indicating like parts in the several figures.

This invention relates to machines for use in the manufacture of shoes for mounting shoes on lasts. Such machines are of particular utility in the manufacture of turn shoes for the purpose of mounting the shoe on the second last after the shoe has been turned, but it will be evident from a consideration of the construction and the manner of operation of the machine herein shown that the invention is not necessarily limited to use with this particular type of shoe.

An important feature of the invention 25 consists in novel means for utilizing a series of repeated impulses for effecting relative movement of a shoe and a last to mount the shoe on the last. An advantage in the use of such means, as distinguished from means 30 for performing the relasting operation by one continuous relative movement of the shoe and the last, is that there is less danger of damaging or of unduly straining the parts of the shoe. The machine herein 35 shown is provided with power operated means, including a continuously driven member, for imparting the series of impulses to the work, and the illustrated organization enables the operator effectively 40 to control the application and the force and incidentally, the amplitude, of such impulses, thus permitting the operation of mounting the shoe on the last to be performed in an expeditious manner with comparatively little effort on the operator's part.

Other features of the invention reside in 45 a novel construction and arrangement of shoe engaging means and last engaging means relatively movable to cause a last to be forced into a shoe, in novel means for gripping a shoe, novel means affording provision for relative lateral adjustment of the shoe and the last, and in various details of construction and combinations of parts, all 50 of which will now be described with refer-

ence to the accompanying drawings and will be pointed out in the claims.

In the drawings,—

Figure 1 is a view in side elevation of a machine in which the invention is embodied, 60 portions of the structure being shown in vertical section,

Fig. 2 is a view on a smaller scale than Fig. 1, showing the machine in front elevation; and

Fig. 3 is a sectional view on the line 3—3 of Fig. 2.

The machine herein shown is provided with means for engaging and gripping or clamping the forepart of a shoe in which 70 a last has been partially inserted, this means being mounted upon a substantially horizontal lever 2 which is pivoted at 4 to an upwardly extending arm 6 on the frame or standard 8 of the machine. Pivoted at 75 10 on the front end of the lever 2 is a clamp support 12 having a guideway extending lengthwise thereof in which is mounted a slide 14 which carries a pad 16 shaped for engagement with the bottom of the sole of 80 the shoe. The slide 14 is freely movable up and down in the guideway and when the machine is idle is supported upon a pin 17 at the lower end of the guideway. Mounted 85 on pivots 18 on the slide 14 are arms 20 which carry pads 22 shaped for engagement with portions of the shoe at the sides and over the top of the forepart, as shown in Fig. 3. The pads 16 and 22 are preferably 90 of rubber or similar material such as to permit the shoe to be firmly gripped and held without injury either to the sole or to the upper. Mounted on pivots 24 on the support 12 are arms 26 which carry rolls 28 positioned for engagement with the outer 95 sides of the shoe gripping arms 20, the outer sides of these arms extending in divergent relation, as shown in Fig. 2. A spring 30 connected to the arms 26 tends to pull these arms toward each other, the inward movement of the arms being limited, when no 100 shoe is in the machine, by engagement of lugs 32 on the arms with the sides of the support 12. When the parts are thus positioned the slide 14 is at its lower limit of 105 movement, in engagement with the pin 17, and by reason of the position of the clamp arms 20 relatively to the operating arms 26, the latter are ineffective to force the clamp arms inwardly. A comparatively light 110

spring 34 connected to pins on the arms 20 tends to spread these arms and to hold them continuously in engagement with the rolls 28, and when the parts are in their idle positions, as above described, the clamp arms 5 are thus opened for the reception of a shoe.

After the forepart of a shoe has been inserted between the clamp arms 20 with its sole in engagement with the pad 16, the 10 clamp arms are caused to close upon the shoe by relative movement of the support 12 and the slide 14 effected as hereinafter described, this relative movement causing the clamp arms to be wedged between the 15 rolls 28 on the arms 26 against the tension of the spring 30. It will be evident by reference to Fig. 3 that the pads 22 are so constructed as to press not only laterally against the shoe but also in the direction 20 of the shoe bottom, thus holding the shoe in firm engagement with the sole supporting pad 16. A comparatively light spring 36 tends to swing the holder 12 backwardly into engagement with a stop lug 38 on the 25 lever 2, while permitting the holder to be swung forwardly into a position convenient for the reception of a shoe and also permitting it to swing relatively to the lever during the operation upon the shoe and the 30 last.

The machine is also provided with last engaging means, which, in the construction shown, comprises a member 44 shaped to embrace the heel end of the last and mounted 35 upon a lever 40 which is pivoted at 42 on the arm 6. Below the front end of the lever 40 is operating means for imparting to the lever a series of upwardly directed impulses. This means comprises a cam 46 fast on a 40 shaft 48 which is driven by means of a belt 50 from a driving shaft 52. A spring plunger 54 which engages under the lever 40 tends to support the lever above the path 45 of movement of the cam 46 while permitting it to be moved by downward pressure of a last into position to be operated by the cam. The lever 2, which carries the shoe engaging means, is connected by means of a rod 55 to a treadle 56 whereby the lever may 50 be moved downwardly against the tension of a spring 58. By the operation of the treadle 56 the shoe and the last are thus moved downwardly to cause the last to engage the member 44 and to force the lever 40 downwardly 55 into position to be operated by the cam 46.

In the operation of the parts above described the holder 12 is swung forwardly and a shoe in which a last has been partially 60 inserted by hand is positioned between the gripping pads 16 and 22 with its sole resting on the pad 16. The support 12 is then swung rearwardly with the shoe and the last to position the heel end of the last over the 65 member 44, and the treadle 56 is depressed.

The heel end of the last is thus moved into engagement with the support 44 and by continued depression of the treadle the support 12 is moved relatively to the slide 14, causing the arms 26, by engagement of their 70 rolls 28 with the outer sides of the clamp members 20, to force these members firmly against the sides and top of the shoe, thus clamping the shoe between the two pads 22 as well as between these pads and the 75 bottom engaging pad 16. By the same movement of the lever 2 the lever 40 is forced downward against the spring plunger 54 into the path of movement of the rapidly 80 rotating cam 46. The cam then imparts a series of rapidly repeated upwardly directed impulses to the lever 40 and the member 44 against the heel end of the last, thus imparting to the last a series of impulses 85 in the direction of the toe end of the shoe and forcing the last forwardly into the shoe in successive steps. Moreover, the operative 90 may so regulate his pressure on the treadle 56 that the contact of lever 40 and cam 46 will be discontinuous, in effect a series of 95 impacts, with the result that the last will receive a series of rapid but separate and distinct blows, instead of a more or less continuous series of impulses. It will be evident 100 that downward pressure upon the treadle 56 also renders the shoe engaging means effective with a tendency to force the shoe over the last, and that the shoe engaging means and the last engaging means are thus mutually coöperative in their operations upon the different respective portions of the work to cause the last to be forced into the shoe. It will also be evident 105 that increase of pressure upon the treadle 56 not only renders the shoe engaging means 110 increasingly effective to force the shoe over the last, but also, by moving the lever 40 farther into the path of movement of the cam 46, increases the leverage of said cam against lever 40 and causes the force of the 115 impulses imparted by the cam to the lever, as well as the extent or amplitude of the oscillatory movement of the lever, to be increased. The downward pressure of the lever 2, moreover, tends to move the support 12 relatively to the clamp holder slide 14 and thus to spread the arms 26 farther apart 120 against the tension of the spring 30, causing the shoe to be held more firmly in proportion to the increase in effectiveness of the means for moving the shoe and the last 125 relatively.

After the last has been firmly seated in the forepart of the shoe by the coöperative action of the cam and the treadle, pressure 125 upon the treadle is released, rendering the spring 58 effective to raise the work from the last support into a position to permit its removal from the machine. After the removal of the work the heel portion of the 130

shoe will be drawn over the last, preferably with the aid of some tool such as a shoe horn.

In the construction shown the member 5 44, which embraces the heel end of the last, is mounted on the lever 40 with freedom for sliding movement transversely of the lever within limits determined by stop screws 45. This construction permits the 10 last to be differently angled with reference to the shoe support for different shoes, such as rights and lefts, and also permits the operator to adjust the last laterally with reference to the shoe during the operation 15 of the machine in such manner as to insure that the last shall be directed accurately toward the toe end of the shoe without undue drag upon either side of the shoe such as would tend to distort the shoe as well as 20 to retard the operation of the machine. It will be evident, moreover, that this construction permits last engaging members of different shapes to be substituted readily, if desired, for different styles of lasts.

25 Having described the invention, what I claim as new and desire to secure by Letters Patent of the United States is:

1. A machine of the class described having, in combination, means for engaging a 30 shoe in which the forepart of a last has been partially inserted, means for engaging the last, and mechanism constructed and arranged to effect a series of relative movements of said shoe engaging means and last 35 engaging means to complete the insertion of the forepart of the last in the shoe by repeated impulses.

2. A machine of the class described having, in combination, means for holding about 40 the forepart a shoe in which a last has been partially inserted, means for engaging the last, and mechanism for imparting to one of said means a series of impulses to complete the insertion of the forepart of the last 45 in the shoe.

3. A machine of the class described having, in combination, means for engaging a last partially inserted in a shoe, means for gripping the shoe by engagement with the 50 bottom of the sole and with the upper at the forepart, and mechanism for imparting to one of said means a series of impulses to complete the insertion of the forepart of the last in the shoe.

55 4. A machine of the class described having, in combination, means for engaging a shoe in which a last has been partially inserted, means for engaging the heel end face of the last, and mechanism for effecting a 60 series of relative movements of said shoe engaging means and last engaging means in a direction to cause the last to be forced into the shoe.

65 5. A machine of the class described having, in combination, means for engaging a

shoe in which a last has been partially inserted, means for engaging the last, and mechanism for imparting to one of said means a series of impulses in a direction lengthwise of the shoe while both said means remain in continuous engagement with the work.

6. A machine of the class described having, in combination, coöperating means constructed and arranged for engagement respectively with the forepart of a shoe and with the heel end face of a last partially inserted in the shoe, and mechanism for effecting a series of relative reciprocatory movements of said shoe engaging means and last engaging means in a direction lengthwise of the shoe to cause the last to be forced into the shoe.

7. A machine of the class described having, in combination, means constructed and arranged to impart to a last partially inserted in a shoe a series of impulses in a direction lengthwise of the shoe to force the last into the shoe, and means for supporting the shoe against the pressure of the last.

8. A machine of the class described having, in combination, a tool constructed for engagement with the heel end face of a last partially inserted in a shoe, and means constructed and arranged to impart to said tool a series of impulses in a direction to force the last into the shoe.

9. A machine of the class described having, in combination, a tool constructed for engagement with the heel end face of a last 100 partially inserted in a shoe, and operating means for imparting to the tool a series of impulses in a direction lengthwise of the last, the tool being supported normally in inoperative relation to said operating means 105 and movable in response to pressure of the last into position to be operated by said means.

10. A machine of the class described having, in combination, a tool constructed to 110 embrace the heel end of a last partially inserted in a shoe, means constructed and arranged to impart to said tool a series of impulses in the direction of the toe end of the shoe, and means for supporting the shoe 115 against the pressure of the last.

11. A machine of the class described having, in combination, coöperating means constructed and arranged for continuous engagement respectively with the heel end of 120 a last partially inserted in a shoe and with the forepart of the shoe, and mechanism for imparting to one of said means a series of impulses in a direction lengthwise of the shoe while the other means supports the 125 work against the thrust of said first means.

12. A machine of the class described having, in combination, a tool for engaging the heel portion of a last partially in a shoe, means for imparting to said tool a series of 130

impulses in the direction of the toe end of the shoe when the tool is moved by the last into operative relation to said means, and means for holding the shoe and the last in 5 position to cause the tool to be operated.

13. A machine of the class described having, in combination, means constructed and arranged to impart to a last partially inserted in a shoe a series of impulses in the 10 direction of the toe end of the shoe, and means for yieldingly supporting the shoe against forward movement with the last.

14. A machine of the class described having, in combination, a tool for engaging the 15 heel end of a last partially inserted in a shoe, operating means toward which the tool is movable for imparting to said tool a series of impulses in a direction lengthwise of the shoe when the tool is moved by the last into 20 operative relation to said means, means for supporting the shoe against the thrust of the tool, and means for moving said supporting means in a direction to cause the tool to be operated by its operating means.

15. A machine of the class described having, in combination, a reciprocatory tool, means for operating said tool, and means for engaging and holding a shoe in which a last has been partially inserted, said means 30 being movable with the shoe and last into and out of position to present the shoe and the last with the heel end face of the last in engagement with the tool.

16. A machine of the class described having, in combination, a tool for engaging the 35 heel portion of a last partially inserted in a shoe, means for imparting to said tool a series of movements in the direction of the toe end of the shoe, means for engaging and supporting the shoe against the thrust of said tool, and manually operated means for moving said shoe engaging means toward the tool.

17. A machine of the class described having, in combination, means for engaging a 45 shoe in which a last is partially inserted, means for engaging the last, mechanism constructed and arranged to impart to one of said means a series of impulses in a direction lengthwise of the shoe to cause the last to be forced into the shoe, and means enabling the operator to vary at will the force 50 of said impulses.

18. A machine of the class described, having, in combination, means for engaging a shoe in which a last is partially inserted, means for engaging the last, mechanism constructed and arranged to effect a series of 55 relative movements of said shoe engaging means and last engaging means in a direction lengthwise of the shoe to cause the last to be forced into the shoe, and means for varying the extent of said movements.

19. A machine of the class described having, in combination, a tool for engaging the 65

heel portion of a last partially inserted in a shoe, operating means for imparting to said tool repeated movements in a direction lengthwise of the last, means for maintaining the tool normally in inoperative relation to said operating means while permitting it to be moved by pressure of the last into position to be operated by said means, means for engaging and supporting the shoe against the thrust of said tool, and means enabling the operator to move said shoe engaging means variably in the direction of the tool to control the force of the impulses imparted to the last. 70 75

20. A machine of the class described having, in combination, a tool for engaging the heel end face of a last partially inserted in a shoe, a lever upon which said tool is mounted, a cam for imparting to said lever operative movements in the direction of the last, 80 spring means tending to position said lever out of operative relation to the cam, means for engaging the shoe, and means for operating said shoe engaging means to cause the last to press upon said lever and force it 85 into position to be operated by the cam. 90

21. A machine of the class described having, in combination, a tool for engaging the heel end face of a last partially inserted in a shoe, a substantially horizontal lever upon 95 which said tool is mounted, operating means under said lever for imparting upwardly directed impulses thereto, yieldable means for normally positioning said lever above the path of movement of said operating means, 100 a second lever extending over said first named lever and having means for engaging the forepart of the shoe, and a treadle connected to said second lever for moving the shoe and the last downwardly to force said 105 first lever into the path of movement of its operating means.

22. A machine of the class described having, in combination, means constructed and arranged to engage the sole and the top 110 of the forepart of a shoe in which a last is partially inserted, last engaging means, and mechanism for effecting relative movement of said shoe engaging means and last engaging means lengthwise of the shoe to cause 115 the last to be forced into the shoe.

23. A machine of the class described having, in combination, shoe engaging means including a device for engaging the shoe frictionally over the top of the forepart, last 120 engaging means, and mechanism for effecting relative movement of said shoe engaging means and last engaging means lengthwise of the shoe to cause the last to be forced into the shoe. 125

24. A machine of the class described having, in combination, means for engaging the forepart of a shoe on the sole and over the top of the upper, means for engaging a last partially inserted in the shoe, and mecha- 130

- nism for effecting relative movement of said shoe engaging means and last engaging means to cause the last to be forced into the shoe.
5. 25. A machine of the class described having, in combination, means for engaging a last partially inserted in a shoe, means for gripping the forepart of the shoe, and mechanism for effecting relative movement of said last engaging means and shoe gripping means to cause the last to be forced into the shoe, said gripping means being constructed and arranged to operate to grip the shoe more firmly in proportion to increase in the force tending to effect relative movement of the shoe and the last.
10. 26. A machine of the class described having, in combination, means for engaging a last partially inserted in a shoe, shoe engaging means including clamp members constructed to hold the forepart of the shoe between them, and mechanism for effecting relative movement of said shoe engaging means and last engaging means to cause the last to be forced into the shoe, said mechanism being constructed to operate said clamp members to vary the clamping pressure on the shoe as the force tending to effect relative movement of the shoe and the last is varied.
15. 27. A machine of the class described having, in combination, means for forcing a last into a shoe, shoe engaging means constructed to clamp the forepart of the shoe and support it against the thrust of the last, and means for varying the clamping pressure of said shoe engaging means on the shoe as the pressure of the last against the shoe is varied.
20. 28. A machine of the class described having, in combination, means for forcing a last forwardly into a shoe, means for engaging the shoe frictionally at opposite sides to support it against the forward thrust of the last, and means for increasing the pressure of said shoe engaging means against the shoe in proportion to increase in the forward pressure of the last in the shoe.
25. 29. A machine of the class described having, in combination, shoe engaging means comprising a device for gripping the forepart of a shoe in which a last has been partially inserted, operating means for forcing the last into the shoe, means for imparting to said shoe engaging means a movement to present the work to said operating means, and means operative during said presenting movement of the shoe engaging means to cause said device to grip the shoe.
30. 30. A machine of the class described having, in combination, shoe engaging means including a pair of clamp members constructed to hold between them a shoe in which a last has been partially inserted, means for engaging the last, mechanism for effecting relative movement of said shoe engaging means and last engaging means to cause the last to be forced into the shoe, and means for causing said mechanism relatively to move said clamp members to force them against the shoe.
35. 31. A machine of the class described having, in combination, means for engaging a last partially inserted in a shoe, means for gripping the forepart of the shoe, means for maintaining said gripping means normally in an open shoe receiving position, treadle operated means for effecting relative movement of said last engaging means and shoe gripping means to cause the last to be forced into the shoe, and means for causing said gripping means to be closed on the shoe by the operation of said treadle means.
40. 32. A machine of the class described having, in combination, means for engaging a last partially inserted in a shoe, shoe engaging means comprising a pair of clamp members constructed to clamp the shoe between them, means for maintaining said members normally in an open shoe receiving position, and means for closing said members against the shoe and for effecting relative movement of the shoe engaging means and last engaging means to cause the last to be forced into the shoe.
45. 33. A machine of the class described having, in combination, means for engaging a last partially inserted in a shoe, shoe engaging means comprising a pair of clamp members constructed to clamp the forepart of a shoe between them, spring means for maintaining said members normally in an open shoe receiving position, mechanism for effecting relative movement of the shoe engaging means and last engaging means to cause the last to be forced into the shoe, and means operated by said relative movement of the shoe engaging means and last engaging means for operating said clamp members to force them yieldingly against the shoe.
50. 34. A machine of the class described having, in combination, means for engaging a last partially inserted in a shoe, shoe engaging means comprising a pair of clamp members constructed to clamp the forepart of a shoe between them and provided with diverging outer surfaces, operating members for engaging the outer surfaces of said clamp members, and mechanism for effecting relative movement of said shoe engaging means and last engaging means to cause the last to be forced into the shoe and for causing said clamp members to be wedged between their operating members and forced against the shoe.
55. 35. In a machine of the class described, clamp members constructed for relative movement to engage the forepart of a shoe, a holder upon which said members are

- 6
- mounted and a support for said holder arranged for relative movement, and means operative upon relative movement of said support and holder for forcing said clamp members against the shoe.
36. In a machine of the class described, clamp members constructed to engage the forepart of a shoe, a slide upon which said members are mounted, a support for said slide, and operating means mounted on said support and arranged to engage said clamp members and force them against the shoe upon relative movement of said slide and support.
- 15 37. In a machine of the class described, shoe engaging means including a device for gripping the forepart of the shoe, a holder upon which said device is mounted, a support for said holder, and means on said support operative upon a relative movement of the support and holder to cause the gripping device to grip the shoe.
- 25 38. In a machine of the class described, a pair of clamp members constructed to engage the forepart of a shoe, a holder upon which said members are pivoted for closing and opening movements, a support for said holder, a pair of arms pivoted on said support for engagement with said clamp members, and means operative upon relative movement of said support and holder for causing said arms to force the clamp members toward the shoe.
- 35 39. In a machine of the class described, a pair of clamp members constructed to engage the forepart of a shoe, a slide upon which said members are pivoted for closing and opening movements, a support upon which said slide is mounted, a pair of arms pivoted on said support for engagement with said clamp members, and spring means tending to move said arms in directions to close said clamp members, said parts being constructed and arranged to cause the clamp members to be wedged between said arms and forced yieldingly against the shoe by a relative movement of said support and slide.
- 45 40. In a machine of the class described, the combination with means for engaging a last partially inserted in a shoe, of means for clamping the shoe, a slide upon which said clamping means is mounted, a support for said slide, and means on said support operative upon a relative movement of said support and slide for forcing said clamping means against the shoe.
- 50 41. In a machine of the class described, the combination with means for engaging a last partially inserted in a shoe, of means for clamping the shoe, a slide upon which said clamping means is mounted, a support for said slide, means on said support operative upon a relative movement of said support and slide for forcing said clamping means against the shoe, a lever upon which
- 5 10 15 20 25 30 35 40 45 50 55 60 65 70 75 80 85 90 95 100 105 110 115 120 125 130
- said support is mounted, and means for operating said lever to move said support in the direction of said last engaging means.
42. A machine of the class described having, in combination, operating means for forcing a last into a shoe, and shoe engaging means movable alternately into position to receive a shoe and a last and into position to present the engaged shoe and last to said operating means.
43. In a machine of the class described, the combination with means for engaging a last partially inserted in a shoe, of shoe engaging means constructed for engagement with the forepart of the shoe, and operating means for moving said shoe engaging means toward the last engaging means, the shoe engaging means being movable relatively to its operating means into position to receive a shoe.
44. In a machine of the class described, the combination with means for engaging a last partially inserted in a shoe, of shoe engaging means constructed for engagement with the forepart of the shoe, and operating means for moving said shoe engaging means toward the last engaging means comprising a lever upon which the shoe engaging means is pivotally mounted for movement alternately into position to receive a shoe and into position to present the shoe and the last in opposed relation to said last engaging means.
45. A machine of the class described having, in combination, shoe engaging means, last engaging means, and mechanism for effecting relative movement of said shoe engaging means and last engaging means lengthwise of the shoe to cause the last to be forced into the shoe, said shoe engaging means and last engaging means being mounted for free relative bodily movement laterally of the shoe.
46. A machine of the class described having, in combination, shoe engaging means, last engaging means, and mechanism for effecting relative movement of said shoe engaging means and last engaging means lengthwise of the shoe to cause the last to be forced into the shoe, said shoe engaging means and last engaging means being mounted for free relative bodily movement laterally of the shoe during their relative movement to force the last into the shoe.
47. In a machine of the class described, the combination with means for engaging a shoe in which a last is partially inserted, of means for engaging the heel portion of the last, and mechanism for effecting relative movement of said shoe engaging means and last engaging means lengthwise of the shoe to cause the last to be forced into the shoe, said last engaging means being adjustable laterally of the shoe.
48. In a machine of the class described,

the combination with means for engaging a shoe in which a last is partially inserted, of means for engaging the heel portion of the last, and mechanism for effecting relative movement of said shoe engaging means and last engaging means lengthwise of the shoe to cause the last to be forced into the shoe, said last engaging means being mounted with freedom for movement laterally of the shoe to permit the operator to determine the direction of the relative movement of the shoe and the last.

49. In a machine of the class described, the combination with means for engaging a shoe in which a last is partially inserted, of means for engaging the last, and mechanism for operating said last engaging means to force the last into the shoe, said last engaging means being adjustable laterally of the shoe and relatively to said shoe engaging means to determine the direction of the movement of the last into the shoe.

50. In a machine of the class described, the combination with means for engaging a shoe in which a last is partially inserted, of a tool constructed to embrace the heel end portion of the last, and means for operating said tool to force the last into the shoe, the tool being adjustable laterally of the shoe and relatively to said shoe engaging means to determine the direction of the movement of the last into the shoe.

51. In a machine of the class described, a tool constructed to embrace the heel end portion of a last partially inserted in a shoe, a support for said tool, means for operating said support to impart to the tool repeated movements in the direction of the toe end of the shoe, and means for supporting the shoe against the thrust of the tool, the tool being movable relatively to its support in directions widthwise of the shoe.

52. A machine of the class described having, in combination, means for engaging a shoe in which the forepart of a last has been partially inserted, means for engaging the last, and mechanism driven from a continuously operating source of power constructed and arranged to effect a series of relative movements of said shoe engaging means and last engaging means to complete the insertion of the forepart of the last in the shoe.

53. A machine of the class described having, in combination, means for engaging a shoe in which a last has been partially inserted, means for engaging the exterior face of the heel end portion of the last, and mechanism driven from a continuously operating source of power for effecting a series of relative movements of said shoe engaging means and last engaging means to complete the insertion of the last in the forepart of the shoe.

54. A machine of the class described having, in combination, means constructed and arranged to deliver upon a last partially inserted in a shoe a series of rapid blows in a direction lengthwise of the shoe to force the last into the shoe, and means for supporting the shoe against the pressure of the last.

55. A machine of the class described having, in combination, a tool constructed for engagement with the heel end face of a last partially inserted in a shoe, and means driven from a continuously operating source of power constructed and arranged to deliver upon said tool a series of blows in a direction to force the last into the shoe.

56. A machine of the class described having, in combination, a tool constructed to embrace the heel end of a last partially inserted in a shoe, means driven from a continuously operating source of power constructed and arranged to deliver upon said tool a series of blows in the direction of the toe end of the shoe, and means for supporting the shoe against the pressure of the last.

57. A machine of the class described having, in combination, means for engaging a last partially inserted in the forepart of a shoe, means for engaging the shoe, and power driven mechanism constructed and arranged to impart to one of said means a series of impulses directed lengthwise of the shoe to complete the insertion of the last in the forepart of the shoe.

58. A machine of the class described having, in combination, means for engaging the exterior surface of the heel end portion of a last partially inserted in a shoe, means for engaging the shoe at the forepart, and power driven mechanism constructed and arranged to impart to one of said means a series of impulses directed lengthwise of the shoe.

59. A machine of the class described having, in combination, a tool constructed for engagement with the exterior surface of the heel end portion of a last partially inserted in a shoe, and power driven mechanism constructed and arranged to impart to said tool a series of impulses directed lengthwise of the shoe.

60. A machine of the class described having, in combination, power driven means constructed and arranged to impart to a last partially inserted in the forepart of a shoe a movement lengthwise of the shoe, and shoe engaging means movable to present a shoe and a last in position to cause the last to be operated upon by said power driven means.

In testimony whereof I have signed my name to this specification.

NORWOOD H. KNOWLTON.
